UNITED STATES PATENT OFFICE.

FREDERICK GEOFFREY LEES JOHNSON, OF WESTMINSTER, LONDON, ENGLAND, AS-
SIGNOR TO VICKERS LIMITED, OF LONDON, ENGLAND, A BRITISH COMPANY.

SHELL FUSE.

Application filed November 7, 1924. Serial No. 748,383.

To all whom it may concern:

Be it known that I, FREDERICK GEOFFREY LEES JOHNSON, a subject of the King of Great Britain, residing at Vickers House, 5 Broadway, Westminster, in the county of London, England, have invented certain new and useful Improvements in or Relating to Shell Fuses, of which the following is a specification.

10 This invention relates to shell fuses of the sensitive percussion type in which the firing pin or needle is normally held in its inoperative position by a centrifugal device composed of one or more bodies which are 15 retained in place by an inertia member and which, after they have been released by the said member on shock of discharge, move outward under the influence of centrifugal force so as to permit the firing 20 needle or pin to be moved rearward to ignite the detonator when the shell strikes an object.

According to the present invention a light 25 shearing wire is provided which passes through holes in the needle carrier of larger size than the wire so that the said wire normally lies out of contact with the front end of the said holes and thus cannot be subjected to shearing stresses if the needle 30 carrier should receive a heavy blow during transport or during the loading of the gun. When however the said centrifugal device has moved into the inoperative position after the shell has left the muzzle of the 35 gun, the air pressure on the front surface of the carrier moves the latter rearward slightly and brings the front ends of the aforesaid holes into contact with the shearing wire. This wire, being of small diameter 40 and made of readily shearable metal (copper for example), becomes sheared on impact of the front surface of the needle carrier with even a slight obstruction such as balloon fabric.

45 The said carrier is preferably composed of two light metal pressings of cup shape fitting one within the other to form a hollow member with the rear wall of which the needle is made integral. The said carrier is thus of very light construction and has little inertia.

A deformable closing disc is preferably placed between the front surface of the needle carrier and an internal flange or

shoulder in an axial hole in which the 55 needle carrier is disposed, this disc when deformed by hand after the parts have been assembled holding the needle carrier against the aforesaid collar halves without impeding the rearward movement of the disc and 60 the needle carrier by air pressure and on impact as aforesaid.

In order that the said invention may be clearly understood and readily carried into effect, the same will now be described more 65 fully with reference to the accompanying drawing which is an axial section of a fuse constructed in accordance with this invention.

A is the fuse body, A¹ is the nose screwed 70 into the fuse body, B is the detonator and B¹ is the detonator holder screwed into the fuse body A. C, C¹ are the two cup-shaped 75 portions of the needle carrier, which portions fit together as shown to form a hollow member of very light weight. The rear portion C carries the needle c and the forward part of this portion C bears against a shoulder a¹ in the nose A¹. This forward part is formed with a recess C² (shown in 80 dotted lines) to receive a pin A² projecting from the nose A¹ into the axial hole in which the needle carrier is disposed; this arrangement prevents the needle carrier 85 from rotating with respect to the nose A¹ during the flight of the shell. The said pin and recess also prevent shearing of the shearing wire D during assembly and also serve to position the needle carrier so as to facilitate the assembly of the shearing 90 wire. This shearing wire passes transversely through the nose A¹ and through the holes c¹, c¹ in the side walls of the carrier parts C, C¹, these holes being made considerably larger in diameter than the shearing 95 wire D so that the latter is normally out of contact with the front and rear ends of these holes. It will be understood that the needle carrier is placed in position from the rear and that the shearing wire is then 100 inserted and suitably secured in position.

E, E are two halves of a collar which is split longitudinally to form the halves. These halves constitute the aforesaid centrifugal device and are situated between, 105 and in contact with, the rear part of the carrier portion C and the front surface of the detonator holder B¹ so as to normally hold

the needle c in the position shown out of contact with the detonator. The front surfaces of the collar halves E , E may be rounded or bevelled as shown and the said halves 5 are normally held in place by an inertia sleeve F having spring fingers f , f bearing against the circumference of the lower parts of the collar halves. These spring fingers are integral with the inertia sleeve as they 10 are formed by making four or more longitudinal slits in a thin ferrule extending from the sleeve, the length of these slits from the front end of the ferrule being varied in accordance with the inertia available. 15 A distance ring F^1 is provided between the inertia sleeve F and an internally projecting flange a^1 on the nose A^1 .

The front face of the carrier portion C^1 is situated slightly to the rear of the front 20 face of the nose A^1 so as to leave a small space between the said front face and a small shoulder or flange a^2 on the nose A^1 . This space is for the purpose of receiving the periphery of a closing disc G which is 25 made of slightly dished form and is inserted with the convex side uppermost. The centre of the disc is then pressed rearwards and this deforms the disc so that the needle carrier is pressed against the collar halves 30 E , E . This deformation of the disc does not increase its diameter and as it is a loose fit in the axial hole of the nose A^1 it is free to move rearwards by air pressure as aforesaid and also on impact with an obstruction. 35 A watertight joint between the said disc and the axial hole in the nose A^1 is obtained by means of varnish after the disc has been deformed as stated above. The use 40 of this disc prevents the possibility of any varnish or other water-proofing material coming in contact with the needle carrier.

The parts of the fuse are normally in the 45 position shown in the drawing with the needle carrier supported by the collar halves E , E and the shearing wire D out of contact with the ends of the elongated holes c^1 . When the shell is fired from a gun, the inertia sleeve F "sets back" and draws the 50 spring fingers f , f clear of the collar halves E , E which are still supporting the needle carrier so that the shearing wire D is still held out of contact with the ends of the elongated holes c^1 . The said spring fingers 55 assist in holding the inertia sleeve in its displaced position. The spin of the shell then causes the collar halves E , E to fly outwardly by centrifugal force and the needle carrier is then no longer supported by these collar halves. The air pressure on the disc 60 G then causes it and the needle carrier to move rearwards slightly to bring the forward ends of the elongated holes c^1 lightly into contact with the shearing wire D . When an obstruction is met the needle carrier 65 is moved forcibly rearwards to bring the

needle against the detonator B to explode the latter, the shearing wire D being sheared by this movement of the needle carrier.

Although in the construction above described the detonator holder B^1 is rigidly secured in the fuse body, it may be slidably mounted therein and normally prevented from moving forwardly by centrifugal locking bodies; in the latter arrangement the detonator holder moves forward by momentum to bring the detonator against the needle on impact or on graze of the shell when the needle carrier does not receive a direct blow.

What I claim and desire to secure by Letters Patent of the United States is:—

1. In a shell fuse of the sensitive percussion type, the combination with the firing needle carrier, the detonator, the centrifugal retaining device and the inertia member 85 normally holding said device in the retaining position, of a light shearing wire passing through the holes in the needle carrier of larger size than the wire so that said wire normally lies out of contact with the front 90 ends of said holes.

2. In a shell fuse of the sensitive percussion type, the combination with the detonator, of a firing needle carrier composed of two light metal pressings of cup shape fitting one within the other to form a hollow member, the needle being made integral with the rear pressing, a centrifugal device for normally holding said needle out of contact with the detonator, an inertia member 95 normally holding said device in the retaining position, and a light shearing wire passing through holes in the needle carrier of larger size than the wire so that said wire normally lies out of contact with the front 100 ends of said holes.

3. In a shell fuse of the sensitive percussion type, the combination with the detonator, of a firing needle carrier composed of two light metal pressings of cup shape fitting one within the other to form a hollow member, the needle being made integral with the rear pressing, a centrifugal device for normally holding said needle out of contact with the detonator, an inertia member 110 normally holding said device in the retaining position by means of spring fingers forming part of said member, and a light shearing wire passing through holes in the needle carrier of larger size than the wire so that said wire normally lies out of contact with the front 115 ends of said holes.

4. In a shell fuse of the sensitive percussion type, the combination with the elements claimed in claim 1, of a deformable disc of convex shape situated between the front surface of the needle carrier and an internal flange or shoulder in an axial hole in which the said needle carrier is disposed, the said disc, when bent from its convex 120 125 130

shape, serving to press the needle carrier against the centrifugal device without increasing the diameter of the disc so that the latter remains free to be pressed rearwards on impact with an obstruction.

5. In a shell fuse of the sensitive percussion type, the combination with the elements claimed in claim 2, of a deformable disc of convex shape situated between the front surface of the needle carrier and an internal flange or shoulder in an axial hole in which the said needle carrier is disposed, the said disc, when bent from its convex shape, serving to press the needle carrier against the centrifugal device without increasing the diameter of the disc so that the latter remains free to be pressed rearwards on impact with an obstruction.

10. In a shell fuse of the sensitive percussion type, the combination with the elements claimed in claim 2, of a deformable disc of convex shape situated between the front surface of the needle carrier and an internal flange or shoulder in an axial hole in which

the said needle carrier is disposed, the said disc, when bent from its convex shape, serving to press the needle carrier against the centrifugal device without increasing the diameter of the disc so that the latter remains free to be pressed rearwards on impact with an obstruction.

15. In a shell fuse of the sensitive percussion type, the combination with the elements claimed in claim 1, of a pin in the nose of the fuse engaging in a recess formed in the needle carrier.

20. In a shell fuse of the sensitive percussion type, the combination with the elements claimed in claim 2, of a pin in the nose of the shell engaging in a recess formed in the rear metal pressing.

25. In a shell fuse of the sensitive percussion type, the combination with the elements claimed in claim 3, of a pin in the nose of the shell engaging in a recess formed in the rear metal pressing.

FREDERICK GEOFFREY LEES JOHNSON.
